PUMP OR IMPELLER

Filed May 24, 1926

FIG. 1.

FIG. 2.

BY

INVENTOR.
HARRY WHITE.
ATTORNEY.

Patented June 14, 1927.

UNITED STATES PATENT OFFICE.

HARRY WHITE, OF KENMORE, OHIO.

PUMP OR IMPELLER.

Application filed May 24, 1926. Serial No. 111,108.

This invention relates to pumps or impellers, such as may be employed, for example, in impelling fluids such as air or water, the particular impeller here shown being adapted for use in wells.

The general purpose of the invention is to provide an improved, self-contained pump or impeller construction, capable of easy and inexpensive manufacture.

Another particular object of the invention is to provide a combined motor and pump or impeller construction in which the rotor of the motor comprises a revolving field which rotates about a fixed armature and which carries the impellers of the pump.

The foregoing and other objects are obtained by the construction illustrated in the accompanying drawings and described below. It is to be understood that the invention is not limited to the specific form thereof shown and described.

Of the accompanying drawings,

Figure 1 is a vertical diametral section through a pump illustrated in a well; and

Figure 2 is a section on line 2-2 of Figure 1.

Referring to the drawings, 10 represents a cylindrical casing having a conical top 11 and a conical bottom 12 secured thereto, a suction pipe 13 being connected to the bottom 12 and a discharge pipe 14 to the top 11.

Casing bottom 12 is formed with a spider 15 supporting a bearing 16 in which is secured, as by a key 17, a hollow shaft 18 which is supported at its upper end by a bearing 19 in a motor casing 20 which is journaled at its upper end in a bearing 21 secured on a spider 22 in the casing top 11 and at its lower end in bearing 17 at 23, the bearing 23 being packed as at 24 against leakage of fluid into casing 20 which is constructed to be water-tight throughout. Casing 20 may also have bearings on shaft 18 at 25 on a flange 18' on said shaft and at 26 so that motor casing 20 will be freely rotatable about shaft 18.

Secured on the outer side of casing 20 are impellers 27, 27, and arranged on the inner side of casing 10 are vanes 28, 28 with which impellers 27 are arranged to cooperate to pump liquid through casing 10 from the inlet 13 to the outlet 14 about the liquid-tight casing 20.

Fixed on shaft 18 within casing 20 is the armature 29 and secured on the inner wall of casing 20 and encircling said arma-

ture is the field 30 of any suitable type of motor, which may be supplied with electricity by means of a lead cable 31 extending into casing 20 through bearing 16 and 60 hollow shaft 18, cable 31 being led up out of the well from the pump to a source of supply of electricity.

The operation of the pump will be understood from the foregoing description. 65 Briefly, it may be described as follows:

After the pump is in situ, the electricity is supplied to the motor, causing the field 30 to revolve about armature 29 and thus rotating casing 20 which completely encloses the 70 motor. The impellers 27 pump the liquid upwardly through casing 10 about casing 20 into the discharge pipe 14.

Modifications of the invention may be resorted to without departing from the spirit 75 thereof or the scope of the appended claims. By suitable modification of the construction shown it may be employed for suction fans and other types of liquid or gas impellers, the essential feature being that the fluid impellers are secured directly onto the revolving member of the motor whereby use of shafting, belting, gearing, etc., between the rotor and the impeller is obviated.

What is claimed is:

1. A self-contained pump comprising a pump casing, a fluid-tight motor casing rotatable within the pump casing, an impeller carried by the motor casing, a vane on the pump casing with which the impeller cooperates, a fixed hollow shaft extending through the motor casing, a motor armature secured on said shaft, a motor field secured within the casing about the armature, and means leading into the pump casing and through the hollow shaft into the motor casing for supplying electricity to the motor.

2. A self-contained pump comprising a pump casing, a fluid-tight motor casing rotatable within the pump casing, an impeller carried by the motor casing, a fixed hollow shaft extending through the motor casing, a motor armature secured on said shaft, a motor field secured within the casing about the armature, and means leading into the pump 105 casing and through the hollow shaft into the motor casing for supplying electricity to the motor.

3. A self-contained pump comprising a pump casing, a fluid-tight motor casing rotatable within the pump casing, an impeller carried by the motor casing, a fixed motor

armature within the motor casing, a motor field secured to the casing about the armature, and means leading into the pump casing and into the motor casing for supplying electricity to the motor.

4. A pump comprising in combination, an outer casing, a second fluid tight casing ro-

tatable therein, an electric motor housed within the second casing for rotating the same, and impellers upon the second casing ¹⁰ for pumping liquids through the first casing around the second casing.

HARRY WHITE.
